Primary Examiner — Susan Bennett Hattan*Assistant Examiner* — Rebecca Tsehay(74) *Attorney, Agent, or Firm* — Sara Centioni Kanos; Nexsen Pruet, LLC(57) **CLAIM**

The ornamental design for a dispersive insert for a pipette tip, as shown and described.

DESCRIPTION

FIG. 1 is a perspective view of a new design of a dispersive insert;

FIG. 2 is a perspective view of a new design of a dispersive insert inside a pipette tip;

FIG. 3 is a side plan view thereof;

FIG. 4 is a cross-sectional, side plan view thereof taken at Line 4-4 shown in FIG. 3;

FIG. 5 is a top plan view thereof; and,

FIG. 6 is a bottom plan view thereof.

The broken lines showing the pipette tip form no part of the claimed design.
